FLASHING TOY CONSTRUCTION

Charles E. Hughes, Chicago, and William S. Walker,
River Forest, Ill.

Application November 18, 1952, Serial No. 321,142

9 Claims. (Cl. 46—228)

Our invention relates to an improved toy of the type wherein a rotor revolves and a light is intermittently energized in accord with the rotations.

Children show a particular attraction to toys of the type wherein an animal figure, such as a bug, or a vehicle figure, such as an airplane, executes movements resembling movements of the figure in normal motion. Some toys have taken advantage of this characteristic by providing handles upon which are mounted rotors to which the animal or vehicle figure is attached in one way or another. Handle motions then cause rotations of the rotor and corresponding movement of the animal or vehicle figure about an orbit to the incident enjoyment of the children.

The toy of the present invention provides, in addition to the moving animal, a light which simulates the light produced by a lightning bug, or similar intermittently energized lighted animal or vehicle. Electric circuit elements are arranged and provided to energize the light intermittently as the rotor turns, thus causing the moving animal or vehicle figure to light intermittently in a manner simulating the intermittent flashes of light produced in the real animal or vehicle, such as a lightning bug.

In addition to simulating a lightning bug, the toy of the present invention may be adapted to simulate the action of an airplane with blinking identification lights. In this instance the figure attached to the rotor is an airplane with lights located in the positions of airplane identification lights.

It is, therefore, a general object of the present invention to provide an improved toy wherein a rotor carries a lighted figure which blinks as the rotor turns.

Another object of the present invention is to provide a toy capable of simulating the lighting action of a lightning bug.

Still another object of the present invention is to provide an improved toy with automatic switch elements which intermittently energize a light as the toy moves.

It is yet another object to provide a simple, inexpensive, self-contained toy which embodies a moving figure and intermittently energizes a light on the figure as the figure moves.

The novel features which we believe to be characteristic of our invention are set forth with particularity in the appended claims. Our invention itself, however, together with further objects and advantages thereof, will best be understood by reference to the following description, taken in connection with the appended drawings, in which:

Figure 1 is a view in perspective of a toy constructed in accordance with the present invention while in use;

Figure 2 is an enlarged view, partially in cross-section, of the toy of Figure 1;

Figure 3 is a cross sectional view through axis 3—3, Figure 2;

Figure 4 is a fragmentary top plan view of Figure 2 as indicated by the axis 4—4, Figure 2;

2

Figure 5 is a view like Figure 4 showing an alternative embodiment of the invention;

Figure 6 is an exploded view in perspective showing the switch elements of the structure of Figure 2;

5 Figure 7 is a view like Figure 6 of an alternative form of the switch elements; and,

Figure 8 is a view like Figure 6 of still another form of the switch elements.

Referring now to Figure 1, there is shown at 10 a handle held by the hand H of the user of the toy. A rotor indicated generally at 12 is received upon the handle 10 and embraces or encloses the top portion of the same. The rotor has an inner cylindrical part 12a which encompasses the handle and an arm part 12b extending radially outwardly therefrom. A bug figure 14 in the form of a lightning bug is disposed at the outer extreme of the arm 12b. A light bulb 16 is located at the end of the arm part 12b in a position simulating that of the illuminated tail portion of a lightning bug.

10 The construction of the handle 10 is shown in greater detail in Figures 2 and 6. It consists of a downwardly extending portion 10a which is gripped by the user of the toy and a headed upper end 10b which is enlarged as shown to define a flat circular upper face 10c. A conducting segment or commutator element 10d of copper or the like extends diametrically across the face 10c of the handle 10. This conducting segment serves to ignite the light intermittently as described in further detail hereafter.

15 20 As shown in Figure 2, the cylindrical part 12a of the rotor 12 has a sleeve portion 13a which fits rather snugly over the handle part 10a to support the same for rotations. At part 13b the rotor part 12a extends outwardly to form a annular shoulder and at part 13c the rotor extends in a tubular shape to the upper threaded extremity 13d.

25 30 The rotor part 12b consists of a threaded cap portion 15a received on the threads 13d. This cap is welded or otherwise attached to the bent radial tube 15b. A light socket 18 is press fitted in the end of the tube 15b as shown in Figure 2 and receives the flashlight type bulb 16. The socket 18 is of copper or similar conducting material, as is the tube 15b, so that the outer shell of the socket establishes a circuit connection to the tube 15b. Since the cap 15a and the cylinder 12a are also of electrically 35 conducting metal, the outer shell of the base of light 16 is in electrically conducting relation with the cylinder 12a.

35 40 45 The rotor part 12b is spring pressed to contact with the tube or cylinder 12a. The top or positive terminal 20a of this battery extends towards the cap 15a and is in electrically contacting relation with the central conducting rivet 22a of the disk 22. An insulated wire 23 is connected at its opposite ends to the conducting rivet 22a and to the socket 18 to form an electrical connection 50 from the center terminal of the light bulb 16 to the positive terminal of the battery 20.

45 55 The disk 22 is spring pressed to contact with the battery 20 by the compression spring 24 which seats at its opposite ends on the cap 15a and on the disk 22.

50 55 The battery 20 has a cardboard insulating sleeve (not shown) of conventional construction. This sleeve prevents direct contact between the tube 12 and the metallic casing of the battery.

The bottom of the battery 20 is not covered by the insulating sleeve. A spring contact arm 26a of the insulating disk 26 extends upwardly and against the exposed bottom surface of the metallic casing of the battery 20 to establish electrical contact therewith. This spring contact is affixed to the disk 26 by a conducting rivet 26b which extends through the disk and protrudes from the opposite side thereof to form a contact button

as shown in Figure 2. A second conducting rivet 26c extends through the disk 26 and protrudes therefrom to form a spaced contact button as shown. This rivet secures a second spring contact arm 26d to the disk 26. The contact arm 26d extends radially outwardly to wipe against the inner surface of the conducting tube 12a. It accordingly is in conducting relation with the outer jacket of the socket 18 and the outer face of the base of the light 16.

The head end 10b of the handle 10 is urged against the disk 26 by the compression spring 28 which seats against the annular shoulder part 13b of the tube 13a and against the annular shoulder formed by the back face of the head 10b of the handle 10.

The energizing circuit for the light 16 can be traced from the battery 20 through the spring contact 26a to the rivet and contact button 26b. The circuit can be further traced from the contact button 26c to the spring contact 26d to the conducting tube 13c. The circuit extends from the tube 13c through the cap 15a and the tube 15b to the outer face of the socket 18. This face of the socket is in contact with the outer shell of the light base and hence one end of the filament of the light 16. The other end of the filament is connected to the central contact of the base of the light 16 so that the circuit can be traced through wire 23 to the contact button 22a and hence the terminal 20a of the battery 20.

It will thus be seen that a complete circuit extends from the battery to the light and is interrupted only between contacts 26b and 26c. These contacts are intermittently bridged by the conducting segment 10d on the handle 10. Since this conducting segment remains stationary while the rotor 12—and the disk 26—rotates, the effect is to intermittently open and close the circuit and thus intermittently light the light 16.

The disk 26 is held in fixed position by the set screw 30, Figure 3. This set screw is threadedly received by the disk 26 and extends through a countersunk hole in the tube 13c as shown.

In the apparatus as above described, the conducting segment 10d bridges the contact buttons 26b and 26c twice for each rotation of the rotor. In the alternative form of Figure 7, the headed end of the handle 10 has a series of four irregularly spaced conducting segments 110d, each extending over less than the full radius of the headed end of the handle. The disk 26 is in this case provided with a pair of radially spaced contact rivets 126b and 126c positioned to be bridged by the conducting segments 110b. The contact rivets 126b and 126c are attached to contact springs similar to 26a and 26d, Figure 2, so that contact 126b is connected to the outer metallic casing of the battery 20 and contact 126c connects with the tube 13c, or vice versa. Thus, as the rotor turns, the contacts 126b and 126c are bridged four times for each rotation and intermittently, thus flashing the light in a manner simulating the lighting of a lightning bug.

Figure 8 shows still another form of the invention wherein a flexible blade 227 extends between contact rivets 226c and 226f which are connected as above described in connection with the rivets 126b and 126c. The headed end of the handle 10 has a series of protuberances 210d over which the flexible blade 227 or cam surfaces 210d ride to be intermittently flexed to contact making position as the rotor turns. This intermittently lights the light 16, Figure 2.

In the form of the invention shown in Figures 1, 2, and 4, the animal figure 14 is in the form of a lightning bug facing inwardly and with the light 16 located at the luminous tail part of the figure. Alternatively, the bug may face outwardly, or be above or below the arm 15b, as desired.

The bug 14 may also be positioned on a circumferential outer portion 15c of the arm 15 as shown in Figure 5. In this case the rotor may rotate in the direction of the arrow of Figure 5 to give a realistic forward motion of the bug 14.

If desired the toy may be made of a plastic casing and arm construction. In this case a second electrical conductor is required, the conductor extending from the outer part of the light base to the conducting rivet 26c.

It will be observed that the battery 20 may be readily removed by unscrewing cap 15a. Thus a replacement may be easily inserted without impairing operation of the toy.

While we have shown and described the present invention as applied to a lightning bug toy, it will be apparent that it may be used with an airplane figure or any other figure desired to light intermittently or periodically as the rotor turns. In the case of an airplane, two or more lights may be put on the figure to simulate identification lights.

In the appended claims I have used the term *rotate* or *revolve "continuously"* to signify the uninterrupted rotation of the rotor as distinguished from a mere change in rotor position from one point to another.

While we have shown and described specific embodiments of the present invention, it will, of course, be understood that many modifications and alternative constructions may be made without departing from the true spirit and scope of the invention. We, therefore, intend by the appended claims to cover all alternative constructions and modifications following within their true spirit and scope.

We claim:

1. A toy comprising in combination: a handle having a headed end with a conducting segment on its top face; a rotor having a tubular portion embracing the headed end of the handle; a battery in the tubular portion of the rotor; an insulating member disposed between the battery and the headed end of the handle, the member having a pair of contacts adapted to be bridged by the conducting segment on the handle; a spring disposed on the tubular portion of the rotor and seating against the headed end of the handle to urge the same against the insulating member; and means defining an electric circuit through the battery, the lamp, and the contacts.

2. A toy comprising in combination: a handle having a headed end with a conducting segment on its top face; a rotor comprising a tubular portion received over the headed end of the handle and a radially extending arm; a figure and a light positioned on the end of the arm; a battery received in the tubular portion of the rotor; an insulating member with a pair of contacts located between the battery and the headed end of the handle, the contacts being adapted to be bridged by the conducting segment on the handle; and means defining an electric circuit from the battery through the contacts to the lamp.

3. A toy comprising in combination: a handle having a headed end with a conducting segment on its top face; a rotor having a tubular portion received over the headed end of the handle; a disk having a pair of spaced contacts adapted to be bridged by the conducting segment and positioned within the rotor and in operative contact with the headed end of the handle; a light on the rotor; a battery within the tubular portion of the rotor; and means defining an electric circuit through the battery, the lamp, and the contacts on the disk.

4. A toy comprising in combination: a handle having a headed end defining a circular track with a protuberance thereon; a rotor received on the handle and adapted to revolve continuously about the same; and having a pressure switch positioned to ride on the track as the rotor turns in relation to the handle, the switch being actuated when it rides over the protuberance; a light on the rotor; means to energize the light; and elements defining an electric circuit from the said last means through the switch to the light.

5. A toy comprising in combination: a handle having a headed end with an electrically conducting segment; a rotor received on the headed end of the handle and adapted to revolve continuously about the same; a light on the rotor; a battery in the rotor; means defining an electric circuit from the battery to the light, said means

including a pair of contacts operable to engage the conducting segment of the headed end of the handle and intermittently light the light.

6. A toy comprising in combination: a handle having a longitudinal axis and a headed end; a rotor received upon the headed end of the handle for rotations about the said axis in complete rotations; a light on the rotor; energizing means for the light; means defining an electric circuit from the energizing means to the light; and switch elements including the headed end of the handle operable to complete the energizing circuit intermittently as the rotor rotates about the handle.

7. A toy comprising in combination: a handle; a two-part rotor swingably supported from the handle to be rotated continuously upon motions of the handle, one part of the rotor being in the form of a cylinder into which the handle extends and the other part of the rotor extending radially outwardly from said one part; a light disposed on said other part of the rotor; energizing means for the light; means defining an electric circuit from the energizing means to the light; and cooperating switch elements on the handle and on the rotor operable intermittently to complete the circuit as the rotor swings.

8. A toy comprising in combination: a handle; a rotor swingably supported from the handle to be rotated continuously about the same upon motions of the handle; a

5 light positioned on the rotor; an energizing means on the rotor to light the light; means defining an electric circuit from the energizing means to the light; and cooperating switch elements on the handle and on the rotor operable intermittently to complete the circuit as the rotor rotates about the handle.

10 9. A toy comprising in combination: a handle having a longitudinal axis; a rotor swingably supported from the handle to be rotated continuously about said axis upon motions of the handle; a light positioned on the rotor; energizing means to light the light; means defining an electric circuit from the energizing means to the light; and cooperating switch elements on the handle and on the rotor operable intermittently to complete the circuit as the rotor rotates about the handle.
